UNITED STATES PATENT OFFICE.

ANDREW STROMDAHL, OF MANCHESTER, NEW HAMPSHIRE.

AUTOMATIC HAMMER.

SPECIFICATION forming part of Letters Patent No. 694,898, dated March 4, 1902.

Application filed March 29, 1901. Serial No. 53,376. (No model.)

To all whom it may concern:

Be it known that I, ANDREW STROMDAHL, a citizen of the United States, residing in Manchester, in the county of Hillsborough and State of New Hampshire, have invented a new and useful Improvement in Automatic Hammers, of which the following is a specification.

My invention relates to the construction of automatic hammers; and it consists of sundry novel elements of construction, presently to be described, whereby the hammer automatically collects tacks or nails, arranges them in order, feeds them one by one to driving mechanism, and enables the workman to utilize the impact of the heavy portions of the hammer as effectively as in the case of an ordinary implement having a solid head.

My improvements are especially adapted to the automatic manipulation of small and light nails, such as tacks used in lasting shoes, and I will therefore describe an embodiment of my invention which is especially adapted to the work of lasting shoes and which, therefore, is a combined hammer and pincers.

In the drawings hereto annexed, which illustrate such an embodiment of my invention, Figure 1 is a side elevation of a lasting-hammer; Fig. 2, a plan view of the head end of the hammer with the cover of the tack-hopper removed; Fig. 3, a vertical sectional view of the head end of the hammer; Fig. 4, a transverse section along the line 4-4 of Figs. 1 and 3 looking from the handle end of the hammer. Fig. 5 is a plan view of the hammer-face; and Fig. 6, a section of the hammer-head, taken across the line 6-6, Figs. 1 and 4, and viewed from below.

In this embodiment of my invention the hammer-handle is made of two articulated parts A and B, which form the two gripping members of the pincers and are jointed at b. The jaws A' and B' are formed integrally with the handles A and B and work in the ordinary manner. The handle member A serves as a basis of attachment for the operative parts which collect, arrange, feed, separate, and drive the tacks. The hopper H is a light but strong box, provided with a suitable cover which is latched at h and is secured to the middle portion A² of the handle A by means of ears h', which are integral with or firmly

fastened to the hopper H, and fastening pins or screws h² h³, which pass through the ears h' and the portion A² of the member A. The hammer-head E is provided with lugs l l, which are suitably perforated to receive the pins h² h³, whereby the hammer-head E is firmly secured to the part A². Both the jaws A' and B' are centrally and longitudinally slotted at B² to receive the tack-raceway R. The raceway R is made of two parallel blades slightly separated from each other. The inclined edges r' of these blades constitute the guides for the tacks as they fall from the gathering-blades r. These gathering-blades are secured to the raceway-blades and automatically tumble the tacks down to the guide r'. A plate h⁴ forms a bottom for the hopper, and a raceway-guard r⁴ is secured by the pin r⁵ in position over the guiding edges r' of the raceway in such manner as to prevent tacks from jumping off the guides, while permitting free movement of the stream of tacks down the guides to the point of delivery to the separating mechanism. The tacks are poured into the hopper H. A few shakes of the hammer will suffice to throw tacks upon the gathering-blades r, which collect the tacks, tumble them to the guides r', where they are received points downward, and are arranged in a regular row along the blades r' under the guard r⁴. A notch r³ serves to prevent the lower part of the row of tacks from moving upward in the raceway, so that although the movements of the hammer in the hands of the workman may dislodge the tacks in the upper part of the raceway there will always be an ample supply of tacks at the delivery end r³ of the raceway. The hammer-head E is cut away at E' to receive the delivery end of the raceway.

The separation of the tacks one by one from the row arranged in the raceway is effected by an escapement F, of which the separator-point F⁴ acts upon the shank of the lowermost tack in the delivery end of the raceway. The tack-separator is made to operate in relation to the movements of the driving mechanism and will be described in detail in connection therewith. Suffice it to say for the present that the separator at proper intervals in the operation of the tool pushes a tack from the delivery end r³ of the raceway into

the delivery-channel p , wherein it falls until arrested by the yielding stops S , which temporarily obstruct the opening of the channel p .

The tack-driving mechanism consists of two connected parts—the driver, which gives each tack the driving-blow, and a driver-actuator, which transmits the impact of the hammer to the driver. In the embodiment of my invention herein shown these parts are represented by the driver P and the driver-actuator D . The driver-actuator is a movable part, standing normally in such position that it shares the impact of the hammer when the workman strikes a blow with it. By this means a sudden vigorous movement is imparted to the driver-actuator. Connections between it and the driver impart to the latter the requisite tack-driving movement. Thus in the form of hammer shown in the drawings the hammer-head E is perforated with slideways P^2 and D^2 , in which the driver P and actuator D slide, respectively. The actuator D is a piston or plunger, having formed upon it the gear-teeth D' , which constitute a rack. The driver P is similarly provided with rack-teeth P' . Between the slideways D^2 and P^2 the hammer-head is laterally perforated with a cylindrical bearing, in which the pinion shaft or block C is inserted. This pinion-shaft is provided with a pinion C^2 , which meshes with both the racks D' and P' . Spring D^3 , coiled around the actuator D , serves by its stress to urge the actuator to its normal position, in which it projects from the hammer-face. When the workman strikes a blow with the hammer, the projecting driver-actuator D shares the impact and is suddenly and forcibly driven into the slideway D^2 , causing the pinion C^2 to rotate and impart to the driver P a movement in reverse direction. The tack which has previously been lodged in the delivery-channel p , which is coincident with slideway P^2 , is thus forced out of the delivery-channel, the stops S yielding to the stroke of the driver. As the workman raises the hammer for the next blow the spring D^3 again projects the actuator D and by means of the connections hereinabove described retracts the driver P . In Fig. 3 the parts are shown in this their normal position.

It is essential to the correct operation of an automatic hammer that a tack or nail feeding mechanism be provided whereby the driving parts are supplied with a tack for each descent of the driver. Many mechanisms have been contrived which serve analogous purposes in other nail-driving tools and machines and may prove adaptable to coöperation with the driving mechanism characteristic of my invention. I have shown in the drawings one form of tack feeder or separator which in practice has served its purpose satisfactorily.

The tack feeder or separator is shown at F in Figs. 1, 3, and 4 and is an escapement which permits the passage of one tack at a time from the raceway into the delivery-chan-

nel p . The feeder is a three-pronged claw, whereof one prong is the finger F^3 , which is armed with the separator-point F^4 , which moves across the lower end r^3 of the raceway, Figs. 3 and 4. The second prong is the guide pin F^2 , which slides in a transverse perforation in the hammer-head E and serves to guide the feeder in its reciprocatory movements. The third prong is the cam-follower F^5 , which coöperates with the cam-surface C' to give the feeder its requisite movements. The cam-surface C' is formed in the end of the pinion-body C and turns under the follower F^5 whenever the pinion is rotated either by the ascent or descent of the actuator D . A leaf-spring F^6 , which is secured by the fastening-screw h^3 , Fig. 1, bears at its end F^7 on the separator F , so as to keep the follower F^5 constantly in contact with the cam C' .

The connection of the tack feeder or separator with the tack-driving mechanism is so arranged that the movements of the separator finger F^3 are timed with reference to the movements of the driver P . Suppose the hammer to be prepared for use by filling the hopper H with tacks. The hammer is then shaken until the raceway R is filled with properly-arranged tacks, the lowermost tack resting with its shank against the separator-point F^4 , the parts being in their normal position, as shown in the several figures. Now if the hammer-head be pressed down upon a bench or if a blow be struck with it the actuator and driver make their movement above described, and then as the hammer is raised the actuator-spring D^3 returns the driving mechanism to its normal position. This double excursion of the driving mechanism turns the cam C' , and the feeder F by means of the follower F^5 is moved out and then in under the influence of the spring F^6 , the feeding-point F^4 moving out and in across the raceway-channel. The outward movement of the feeding-finger F^3 allows the lowermost tack to pass by the point F^4 , when it would fall into the delivery-channel p were it not for the fact that the driver P fills the channel. When the driver P is retracted, the feeding-finger inserts its point F^4 behind this tack and wedges it out into the tack-delivery channel p , wherein it falls, to be arrested by the stops in the delivery-channel. These stops may be double or single and may be arranged in the path of the driver whenever the designer of a hammer embodying my improvements may choose to put it. The function of the stops is to hold a tack in the delivery-channel point downward in readiness to be driven by the driver P .

The stops shown in the drawings are arranged as follows: A transverse groove or path e is cut in the hammer-head, crossing the delivery-channel p , Fig. 5. Into this channel the stop-blocks S are inserted and are there held by the spring s' , which passes into a recess e' , cut on either side of the head E , and into holes s , cut for the purpose in the

blocks S. The stress of the spring s' is exerted to clasp the blocks S together, as shown in Fig. 6. In Fig. 4 the uniting ends of the blocks S are shown tapered from above in order to admit the driver P. When a tack has been separated from the row in the raceway and drops into the delivery-channel p, it rests point downward upon the stop-blocks S. Then at the next descent of the driver P the tack is driven, the blocks separating in response to the stroke of the driver.

Occasionally it is desirable to suspend the automatic action of the hammer, so as to use the hammer in the ordinary way. For this purpose I provide the catch K, which is the end of a latch inserted in a suitable perforation in the side of the hammer and is seen in Figs. 1 and 3. This latch is an extension from the bar k², with which it is connected by the offset k'. The bar k² slides in lugs k⁴, which are secured to or form part of the plate k⁵, which is fastened to the hammer-handle in such position that the finger-hold k³, which is suitably bent outward, lies within easy reach of the workman's forefinger. A spring k⁶ constantly urges the latch k toward the hammer-head E.

On the side of the actuator D which lies opposite the latch end k there is a notch d, which registers with the latch end K when the actuator is raised to its farthest entrance into the hammer-head and when the end of the actuator is flush, or nearly so, with the face of the hammer-head, Fig. 3. So long as the workman presses on the finger-hold k³ the actuator slides up and down without hindrance; but should the workman wish to suspend the automatic action of the hammer he lets go the finger-hold k³ at the time he strikes a blow, and the spring k⁶ then thrusts the latch end K into the notch d, when the latter registers with it and holds all the automatic parts in restraint. Then the hammer may be used like an ordinary tool.

What I claim, and desire to secure by Letters Patent, is—

1. In an automatic hammer, the combination with tack-feeding devices of a hammer-head, a movably-mounted tack-driver, a driver-actuator movably mounted in such position as to share the impact of the hammer, and connections between the driver and the actuator whereby movement of the actuator in response to impact actuates the driver.

2. In an automatic hammer, the combination of a hammer-head, a hopper, a raceway leading therefrom to a driver, the driver, a driver-actuator movably mounted and normally projecting from the hammer-face, and connections between the actuator and driver whereby movement of the actuator transmits to the driver a movement in reverse direction to that of the actuator.

3. In an automatic hammer, the combination of a hammer, a hopper, a raceway leading therefrom to a driver, the movably-mount-

ed driver, a movable driver-actuator mounted in position to share the impact of the hammer, and connections between the actuator and the driver whereby movement of the former in response to impact transmits a driving movement to the latter.

4. In an automatic hammer, the combination of a hammer, a hopper, a raceway leading therefrom to a delivery-channel, the delivery-channel, a driver movable therein, a movable driver-actuator mounted in position to share the impact of the hammer, and connections between the actuator and the driver whereby movement of the former in response to impact actuates the latter to force a tack out of the delivery-channel.

5. In an automatic hammer, the combination of tack-feeding devices, a hammer-head, a movably-mounted driver, a movably-mounted driver-actuator, normally extended beyond the face of the hammer-head, and connections between the actuator and the driver whereby movement of the former in response to impact transmits a driving movement to the latter.

6. In an automatic hammer, the combination of a hammer, a hopper, a raceway leading therefrom to a driver, the movably-mounted driver, a movable driver-actuator normally extending beyond the face of the hammer-head, and connections between the actuator and the driver whereby movement of the former in response to impact transmits a driving movement to the latter.

7. In an automatic hammer, the combination of a hopper, a raceway leading therefrom to a delivery-channel in a hammer-head, the hammer-head, a driver movably mounted in the hammer-head, a movably-mounted driver-actuator, normally extended beyond the face of the hammer-head, and connections between the actuator and driver whereby movement of the former in response to impact actuates the latter to force a tack out of the delivery-channel.

8. In an automatic hammer, the combination with tack-feeding devices, of a hammer-head, two slideways therein, a driver slidably mounted in one slideway, a driver-actuator slidably mounted in the other, the actuator normally extended to such position as to share the impact of the hammer, and connections between the actuator and the driver whereby movement of the former in response to impact transmits driving movement to the latter.

9. In an automatic hammer the combination of a hopper, a raceway leading from the hopper to a delivery-channel in a hammer-head, the hammer-head, two slideways therein, one coincident with the delivery-channel, a driver sliding in said slideway, the other slideway bearing a movable driver-actuator which is normally extended beyond the face of the hammer-head, and connections between the actuator and driver whereby movement

of the former in response to impact of the hammer actuates the latter to force a tack out of the delivery-channel.

10. In an automatic hammer, the combination with tack-feeding devices of a hammer-head means for yieldingly holding a tack in the path of a tack-driver, the movably-mounted tack-driver, a driver-actuator movably mounted in such position as to share the impact of the hammer, and connections between the driver and the actuator whereby movement of the actuator in response to impact actuates the driver.

11. In an automatic hammer, the combination of a hammer-head, a hopper, a raceway leading therefrom to a driver, the driver, a yielding stop in the path of the driver, a driver-actuator movably mounted and normally projecting from the hammer-face, and connections between the actuator and driver whereby movement of the actuator transmits to the driver a movement in reverse direction to that of the actuator.

12. In an automatic hammer, the combination of a hammer, a hopper, a raceway leading therefrom to a driver, the movably-mounted driver a yielding stop in the path of the driver, a movable driver-actuator mounted in position to share the impact of the hammer, and connections between the actuator and the driver whereby movement of the former in response to impact transmits a driving movement to the latter.

13. In an automatic hammer, the combination of a hammer, a hopper, a raceway leading therefrom to a delivery-channel, the delivery-channel, a driver movable therein, a yielding stop in the path of the driver, a movable driver-actuator mounted in position to share the impact of the hammer, and connections between the actuator and the driver whereby movement of the former in response to impact actuates the latter to force a tack out of the delivery-channel.

14. In an automatic hammer, the combination of tack-feeding devices, a hammer-head, a movably-mounted driver, a yielding stop in the path of the driver, a movably-mounted driver-actuator, normally extended beyond the face of the hammer-head, and connections between the actuator and the driver whereby movement of the former in response to impact transmits a driving movement to the latter.

15. In an automatic hammer, the combination of a hopper, a raceway leading therefrom to a driver, the movably-mounted driver, a yielding stop in the path of the driver a movable driver-actuator normally extending beyond the face of the hammer-head, and connections between the actuator and the driver whereby movement of the former in response to impact transmits a driving movement to the latter.

16. In an automatic hammer, the combination of a hopper, a raceway leading therefrom to a delivery-channel in a hammer-head, the hammer-head, a driver movably mounted in

the hammer-head a yielding stop in the path of the driver, a movably-mounted driver-actuator, normally extended beyond the face of the hammer-head, and connections between the actuator and driver whereby movement of the former in response to impact actuates the latter to force a tack out of the delivery-channel.

17. In an automatic hammer the combination with tack-feeding devices, of a hammer-head, two slideways therein, a driver slidably mounted in one slideway, a driver-actuator slidably mounted in the other, the actuator normally extended to such position as to share the impact of the hammer, a yielding stop in the driver-slideway, and connections between the actuator and the driver whereby movement of the former in response to impact transmits driving movement to the latter.

18. In an automatic hammer the combination of a hopper, a raceway leading from the hopper to a delivery-channel in a hammer-head, the hammer-head, two slideways therein, one coincident with the delivery-channel, a driver sliding in said slideway, the other slideway bearing a movable driver-actuator which is normally extended beyond the face of the hammer-head a yielding stop in the delivery-channel, and connections between the actuator and driver whereby movement of the former in response to impact of the hammer actuates the latter to force a tack out of the delivery-channel.

19. In an automatic hammer, the combination with tack-feeding devices of a hammer, tack-driving mechanism consisting of a driver and a driver-actuator, each provided with a rack which meshes with a pinion, the pinion, the driver-actuator being mounted in such position as to share the impact of the hammer, and by its movement in response to such impact to actuate the driver through the pinion.

20. In an automatic hammer, the combination of a hammer-head, a hopper, a raceway leading therefrom to a driver, the driver, a driver-actuator movably mounted and normally projecting from the hammer-face, the driver and its actuator being provided each with gear-teeth which mesh with an intervening pinion, and the pinion, whereby movement of the actuator transmits to the driver a movement in direction reverse to that of the actuator.

21. In an automatic hammer, the combination with tack-feeding devices, of a hammer-head, two slideways therein, a driver slidably mounted in one slideway, a driver-actuator slidably mounted in the other, the actuator normally extended to such position as to share the impact of the hammer, the driver and actuator provided with gear-teeth which mesh with an intervening pinion, and the pinion, whereby movement of the actuator in response to impact transmits driving movement to the driver.

22. In an automatic hammer the combination of a hopper, a raceway leading from the hopper to a delivery-channel in a hammer-head, the hammer-head, two slideways therein, one coincident with the delivery-channel, a driver sliding in said slideway, the other slideway bearing a movable driver-actuator which is normally extended beyond the face of the hammer-head, the driver and actuator provided with gear-teeth which mesh with a pinion, and the pinion, whereby movement of the actuator in response to impact of the hammer actuates the driver to force a tack out of the delivery-channel.

23. In an automatic hammer, the combination of a hopper, a raceway leading therefrom, tack-driving mechanism consisting of a driver and driver-actuator, each provided with a rack, a pinion meshing with the said racks, the driver-actuator being mounted in such position as to share the impact of the hammer and by its movement in response to such impact to actuate the driver through the pinion, and tack-delivery mechanism consisting of a tack-escapement and connections therewith to the tack-driving mechanism, whereby tack-feeding and tack-driving operations are alternated.

24. In an automatic hammer, the combination of a hopper a raceway leading therefrom, a hammer-head, a driver, a driver-actuator, geared together by a pinion, the pinion, a tack-escapement in the raceway, connections between the escapement and the pinion, whereby tack-feeding movement of the escapement alternates with movement of the tack-driver and actuator.

25. In an automatic hammer, the combination with tack-feeding devices, of a hammer-head, a movably-mounted tack-driver, a driver-actuator movably mounted in such position as to share the impact of the hammer, and connections between the driver and the actuator whereby movement of the actuator in response to impact actuates the driver and a catch under the control of the operator, whereby the driver-actuator may be restrained from movement.

26. In an automatic hammer, the combina-

tion with tack-feeding devices, of a hammer-head, a movably-mounted tack-driver a driver-actuator movably mounted in such position as to share the impact of the hammer, and connections between the driver and the actuator whereby movement of the actuator in response to impacts actuates the driver and a spring-actuated catch, under the control of the operator, and normally urged toward a position of engagement with the driver-actuator, whereby the actuator may be restrained from movement.

27. In an automatic hammer, the combination with tack-feeding devices, of a hammer, tack-driving mechanism consisting of a driver and a driver-actuator, each provided with a rack which meshes with a pinion, the pinion, the driver-actuator being mounted in such position as to share the impact of the hammer, and by its movement in response to such impact to actuate the driver through the pinion, and a catch under the control of the operator whereby the tack-driving mechanism may be restrained from movement.

28. In an automatic hammer the combination with tack-feeding devices, of a hammer-head, two slideways therein, a driver slidably mounted in one slideway, a spring-controlled driver-actuator slidably mounted in the other, the actuator normally extended by the force of its spring to such position as to share the impact of the hammer, and connections between the actuator and the driver whereby movement of the former in response to impact transmits driving movement to the latter.

29. In an automatic hammer, the combination of pincers, a hammer-head secured thereto, tack-driving devices in the hammer-head, a tack-reservoir and raceway leading therefrom to the tack-driving devices, the pincer members provided with a slot for the admission of the tack-raceway.

Signed by me, at Manchester, New Hampshire, this 26th day of March, 1901.

ANDREW STROMDAHL.
